(57) **CLAIM**

The ornamental design for a wheel for a mobility assistance apparatus, as shown and described.

DESCRIPTION

FIG. 1 is a front elevation view of a first embodiment of a wheel for a mobility assistance apparatus, showing our new design;

FIG. 2 is a rear elevation view thereof;

FIG. 3 is a side elevation view thereof;

FIG. 4 is a side elevation view thereof;

FIG. 5 is a top plan view thereof;

FIG. 6 is a bottom plan view thereof;

FIG. 7 is a top plan perspective view thereof;

FIG. 8 is a front elevation view of a second embodiment of a wheel for a mobility assistance apparatus, showing our new design;

FIG. 9 is a rear elevation view thereof;

FIG. 10 is a side elevation view thereof;

FIG. 11 is a side elevation view thereof;

FIG. 12 is a top plan view thereof;

FIG. 13 is a bottom plan view thereof; and,

FIG. 14 is a top plan perspective view thereof.
